UNITED STATES PATENT OFFICE

2,258,600

UPPER SHAPING MACHINE

Karl Engel, Swampscott, Mass., assignor to United Shoe Machinery Corporation, Borough of Flemington, N. J., a corporation of New Jersey

Application February 23, 1940, Serial No. 320,391

47 Claims.

(Cl. 12—97)

This invention relates to upper-shaping machines and is herein illustrated in its application to machines for shaping uppers without the aid of a last.

The term "upper," as hereinafter employed, is in most cases used generically and includes the counter stiffener and is to be so construed unless the context requires that the term be specifically construed.

In the manufacture of some types of shoes it is advantageous to shape the upper without the aid of a last in order that the interior of the upper may be accessible for the performance of operations subsequent to the upper-shaping operation. An example of shoe constructions which require the shaping of the upper without the aid of a last is disclosed in United States Letters Patent No. 2,212,514, granted August 27, 1940, on an application filed in my name.

In the manufacture of shoes in accordance with methods which require the shaping or molding of the back part or quarter before it is attached to the forepart or vamp it is a usual practice to shape such back parts without the aid of a last, the last ordinarily being inserted into the upper after the molded back part has been attached to the vamp.

It is an object of the present invention to provide an improved upper-shaping machine adapted to shape uppers, or the back parts or quarters of uppers, which have not been assembled on lasts. It is a further object of the invention to provide in such a machine suitable means for forming a well-defined inwardly extending flange in the rear part of the upper to facilitate the attachment of the rear part of the upper to a sole in accordance with the method set forth in my patent above referred to, or in any other suitable manner.

In manufacturing shoes in accordance with methods which require a closed upper to be initially shaped without the aid of a last, it is desirable to provide means for shaping the instep portion of the upper in order to provide in that portion of the upper sufficient space for the foot of the wearer. This is particularly desirable when, as in the method set forth in my patent above referred to, the last is not inserted into the upper until the manufacture of the shoe is nearly completed, and, consequently, the shoe is on the last but a short time. Accordingly, it is an object of the present invention to provide in an upper-shaping machine suitable means for shaping the instep portion of the upper.

In the manufacture of high-grade shoes,

manufacturers often prefer to provide their uppers with heel stiffeners or counters which have not been molded, or have been only partially molded, prior to their insertion into the upper. 5 The final shaping of such counters is effected in shaping the rear part of the upper. This shaping in most cases requires the formation in the counter of an inwardly extending flange. Counter materials commonly used for counters of this type are of a fibrous nature and the flange formed in the counter in the upper-shaping operation tends to spring back to its original position after the flange forming pressure is released. With this in view, it is an object of the present invention to provide flange forming means adapted to bend the flange beyond the desired angular position of the flange relatively to the body of the counter to an extent equal to the normal reactive movement of the flange.

With the above and other objects in view, as will hereinafter appear, the present invention consists in the provision in an upper-shaping machine of means for shaping an end portion of an upper, means for holding the upper under lengthwise tension during the shaping operation and means for applying pressure to the instep portion of the upper in a direction generally heightwise of the upper to shape said instep portion while the upper is held by said shaping means and said tensioning means. The upper shaping means, as herein illustrated, comprises a pair of rear part shaping molds which are mounted in mold carriers and have yielding connections to the carriers which permit movement of the molds relatively to the carriers for a purpose now to be described. In order to obviate any pinching or abrading of the rear or back-seam portion of the upper by closing action of the molds, the shaping of the rear part of the upper is effected by relative movement of the molds and the inner heel form lengthwise of the upper combined with the closing action of the molds, and said closing action is completed before such lengthwise movement has brought the back-seam portion of the upper into contact with the end portions of the molds. The latter part of such lengthwise movement wedges the molds away from each other so that their rear end portions are separated slightly when the upper comes in contact with them, and consequently there is no possibility of damage to the back-seam portion of the upper by pinching it between the adjacent end portions of the molds.

For holding a closed upper under lengthwise tension during the heel-shaping operation the illustrated machine, in accordance with a fur-

ther feature of the invention, is provided with means for gripping the toe end of an upper mounted on the inner heel form, means for gripping opposite side portions of the forepart of the upper, said toe gripping means and side gripping means being yieldingly connected to a fixed portion of the machine in order that lengthwise tension may be imparted to the upper as the inner heel form advances to force the rear part of the upper into the rear part shaping molds. In accordance with a further feature of the invention the side grippers are carried by a slide mounted on the member which carries the inner heel form and movable on said member in a path inclining downwardly and heelwardly relatively to the upper. As the inner heel form advances into the rear part shaping molds, the slide is held back by its yielding connection to said fixture and there is a differential movement of the heel form carrying member relatively to the slide which causes the slide to move heightwise of the upper, tensioning the forepart of the upper about the instep-shaping means. The lengthwise and heightwise tension imparted to the upper is maintained during the remaining operations of the machine and serves to hold the upper on the heel form in proper position for the operation of the rear part shaping means and to hold the forepart of the upper during the operation of the instep-shaping means.

In accordance with a further feature of the invention, the instep portion of the upper is shaped by a member constructed and arranged to operate against the inner surface of the instep portion only while the forepart of the upper is held by the gripping means. The illustrated instep-shaping member is carried by the inner heel form and arranged for movement generally heightwise of the upper.

For forming an inwardly extending flange in the rear part of an upper, or in a back part, or quarter, which has not been attached to a vamp, the illustrated machine, in accordance with a further feature of the invention, is provided with a wiper for wiping the lasting margin of an upper on the inner heel form inwardly over the heel seat face of the form while the upper is held under lengthwise tension, and for assisting in the flanging of the overwiped margin, a flange former is arranged for operative movement heightwise of the upper to press the overwiped margin against the heel form after the wiper has completed its overwiping movement. In order that the flange former may bend the margin of the upper beyond its desired angular position so that the reactive movement of the counter with which the upper is provided will leave the margin of the upper in the desired angular position, the heel seat face of the inner heel form, in accordance with a further feature of the invention, is recessed and the flange former is constructed and arranged to press the margin of the upper into the recess in the form, the flange former and heel form acting as dies to shape the margin of the upper. The illustrated flange former moves in a direction perpendicular to the path of operative movement of the wiper through a suitable opening provided in the wiper. In order to obviate possible dislocation of the overwiped margin of the upper by the retraction of the wiper, means is provided for automatically lifting the wiper away from the upper during the interval between the operation of the wiper and its retraction.

For positioning the rear part of the upper heightwise thereof on the inner heel form, the illustrated machine is provided with novel gaging means herein illustrated as a pair of gage members constructed and arranged to engage the edge of the lasting margin, and connections are provided from the wiper to the gage members for moving the gage members out of the path of movement of the wiper as the wiper is advanced.

10 These and other features of the invention will now be described with reference to the accompanying drawings and pointed out in the appended claims.

In the drawings,

Fig. 19 is a section taken on the line XIX—XIX of Fig. 18;

65 Figs. 20 and 21 are detail views illustrating the operation of the instep stretching member; and

Fig. 22 is a detail view in side elevation illustrating the mechanism for operating the instep stretching member.

70 Referring to Fig. 1, the illustrated machine comprises a frame 30 having a flat top 32 which inclines downwardly and forwardly toward the work supports of the machine. Mounted in the upper portion of the machine for rectilinear

movement in a direction parallel to the flat top 32 is a slide 158 which carries molds 44 for shaping the rear part of a shoe mounted on the work supports. Fulcrumed at 204 on brackets extending rearwardly from the upper portion of the frame is a head comprising two plates 202 spaced apart from each other widthwise of the machine and secured to a rigid channel member 36 which forms an arch over the forward portions of the plates 202. Mounted between the plates 202 is a slide 200 which carries a wiper member 56. The operating mechanisms are covered by a hood 34 secured to the member 36 and extending rearwardly from said member and downwardly to the back of the machine frame, said hood being sufficiently flexible to permit a slight upward swinging movement of the machine head. During the advancement of the wiper 56, the head is so positioned that the wiper travels in a path parallel to the path of movement of the slide 158 which carries the rear part shaping molds. Before the wiper is retracted, the head is swung upwardly slightly to bring the wiper out of contact with the work thus obviating any possible dislocation of the work by the retraction of the wiper. For mounting the work-supporting mechanism a bracket 38 is secured to the front of the frame and has a top surface 40 inclined forwardly and downwardly in a plane parallel to the plane of the top surface 32 of the frame 30. The top of the bracket 38 provides a mounting for a slide 72 which carries an inner heel form 42 against which operate the rear part shaping molds 44. During the operation of the machine the upper is held in a predetermined position on the form 42 by toe grippers and side grippers hereinafter described.

For actuating the operating parts of the machine a motor 46 is mounted on the base of the frame and arranged to drive a pulley 48 which operates a pulley 50 loosely mounted on a cam shaft 52. For operatively connecting the pulley 50 to the cam shaft, the machine is provided with a one-revolution clutch mechanism (not shown) which is operated by the depression of a treadle 54. Upon depression of said treadle the cam shaft makes one complete revolution in a clockwise direction as seen in Fig. 1, turning cams mounted on said shaft, the cams being suitably contoured to actuate the operating parts of the machine in predetermined time relation through linkages illustrated generally in Fig. 1 and hereinafter more fully described.

In the course of the machine cycle the inner heel form 42 moves upwardly and rearwardly while the rear part embracing molds 44 move downwardly and forwardly and close upon the rear part of an upper on the form. The upper may be provided with any suitable counter stiffener but the illustrated machine is particularly adapted to operate on an upper provided with a counter which has not been molded or has been only partially molded. The upper-shaping mechanism of the illustrated machine is well-adapted to complete the shaping of such a counter and form an inwardly extending flange therein. After the molds 44 have closed on the upper the rear part wiping member 56 advances and wipes the lasting margin projecting above the inner heel form 42 over the edge of the form. As the wiper advances, it carries with it a flange forming or molding member 58 and when the wiper comes to the limit of its operating movement, the flange former is arranged for downward movement through an opening provided in

the wiper member to form or mold the overwiped lasting margin of the upper against the top surface of the form 42. It will be understood that the principal function of the flange former is to shape or flange the bottom margin of a non-molded counter with which the upper has been provided. During the operation of the flange former an instep stretching and shaping member 60 is swung downwardly to shape the instep portion of the upper, the upper being supported for the instep shaping operation by the side grippers, now to be described.

Referring now to Fig. 2, which illustrates the side grippers and their operating mechanism, the fixed jaws 62 of said grippers are formed in a slide 64 having inwardly extending T-shaped tongues 66, mounted in suitable grooves provided in a rearward extension 68 (Fig. 3) of an L-shaped member 70 secured to a slide 72 mounted in the bracket 38. Referring again to Fig. 2, two movable gripper jaws 74 are formed in the lower portions of two vertical levers 76 and are arranged to act against the fixed jaws 62. The levers 76 are pivoted to lugs 78 extending outwardly from the slide 64. These levers 76 as seen in side elevation (Fig. 7) are generally U-shaped and their dimension lengthwise of the upper is such that they engage a substantial extent of the lasting margin. For simultaneously operating the movable gripper jaws 74, a hand lever 80 (Figs. 2 and 7) is mounted on a cross pin 82 carried by upward extensions 84 of the slide 64 and pivoted at its rear end to a member 86 swivelled on a pin 88 connecting the inner ends of toggle links 90 the outer ends of which are pivoted respectively to the levers 76 (Fig. 16).

During the rearward and upward movement of the inner heel form 42, the toe end of the upper is held by grippers, now to be described, which operate to tension the upper during said movement of the form. Referring to Figs. 2, 3, and 20, the illustrated toe grippers comprise a fixed jaw 92 (Fig. 2) formed in a downwardly offset portion 94 of a plate 96 which has tongue and groove connections 97 to a standard 98 secured to the bracket 38, said connections affording sliding movement of the plate 96 in a direction parallel to the plane of the top surface 40 of the bracket 38. Co-operating with the fixed gripper jaw 92 is a movable gripper jaw 100 (Fig. 2) formed in a central downwardly offset portion 102 of a plate 104 arranged for vertical movement relatively to the plate 96, such movement being controlled by headed screws 106 extending through holes in the plate 96 and into the end portions of the plate 104. For operating the gripper jaw 100, an eccentric 108 provided with a hand lever 110 is mounted on a cross pin 112 between abutments provided by the inner ends of bearings 114 extending inwardly from downward extensions 116 of the plate 96. Referring to Fig. 20 the toe grippers and the side grippers are yieldingly held at the limit of their forward movement by springs 118 and 120 respectively, there being two such springs for each gripper assembly. The springs 118 encircle rods 122 extending forwardly from the end portions of the plate 104 and are confined between nuts 124 on said rods and brackets 126 extending outwardly from the standard 98, said brackets being provided with holes through which the rods 122 slide. The springs 120 encircle rods 128 extending rearwardly from bosses 130 in the upper portion of the standard 98. The rods 128 extend through holes in ears 132 extending outwardly from the slide 64 and the springs 120 are confined between

said ears and nuts 134 on said rods. The springs 118 and 120 yieldingly hold the toe gripper and the side grippers at the limit of their movement toward the standard 98. It will be understood that the springs act to tension the upper lengthwise thereof during the movement of the inner heel form 42 away from the standard 98 in the course of the operation of the machine. This movement of the inner heel form is effected by moving the L-shaped member 70 in which the inner heel form is mounted, said member having a deep groove 136 (Figs. 2 and 3) in which the shank portion 138 of the heel form is secured by a screw 140. In order that the side grippers may tension the upper heightwise during the movement of the inner heel form away from the standard 98, the grooves 61 (Fig. 3) in which the slide 64 is mounted, are arranged at an inclination such that the slide 64 and the side grippers carried thereby have a movement heightwise of the upper during the actuation of the L-shaped member 70 which movement causes the side grippers to tension the upper heightwise against the instep-shaping member preparatory to the operation of said member.

For positioning the rear part of an upper, for example, the upper 142 illustrated in Figs. 6, 7, and 8, heightwise on the inner heel form 42, the illustrated machine is provided with two gage members 144 constructed and arranged to act against the edge of the lasting margin of the rear part of the upper. Each gage member acts on one side of the rear part of the upper and extends along the curve of the rear part of the upper almost to the back seam (Fig. 6). The upturned ends 150 (Fig. 7) of the gage members are secured to upturned ends 148 of bell crank levers 146 and are adjustable vertically thereon. The rear portions of the bell crank levers 146 have slots 152 (Fig. 6) which receive pins 154 extending upwardly from the ends of diverging arms of a member 156 secured to a slide 158 which actuates the rear part embracing molds 44. During the closing of the molds on the upper, the slide 158 moves toward the rear part of the upper and it will be seen that this movement of the slide swings the bell crank levers 146 in a direction to move the gage members 144 into a position remote from the upper as shown in Fig. 9, thus providing clearance for the advancement of the wiper assembly.

The rear part embracing molds 44 are metal blocks each of which has the contour of one-half of the rear part of a shoe formed in its inner surface 160 (Fig. 10). The molds 44 are mounted on carriers 162 having inwardly extending flanges 164 to which the mold members are connected by headed screws 166 extending through short slots 168 provided in lugs 170 extending outwardly from the mold members and affording relative movement of the mold members and their carriers widthwise of the shoe. The mold members are yieldingly urged toward each other by springs 172 (Fig. 6) interposed between the mold members and their carriers. The carriers 162 are fulcrumed at 174 on arms 176 extending inwardly and forwardly from opposite sides of the upper portion of the frame 30. Referring to Figs. 1 and 9, the rear part embracing molds 44 are operated by movement of the slide 158 toward the rear part of the upper. This slide is mounted for rectilinear movement in a guideway in the upper portion of the machine frame and has fulcrumed at opposite sides of its forward extremity two arms 178 (Fig. 9) the outer

ends of which are fulcrumed to the rear portions of the carriers 162. As the slide advances from its position in Fig. 6, to its position in Fig. 11, the arms 178 exert a toggle action on the carriers 162 closing the rear part embracing molds on the upper.

For simultaneously operating the inner heel form 42 and the rear part embracing molds 44 a cam 180 on the cam shaft 52 is arranged to act against a roll 182 at the lower end of a bent lever 184 fulcrumed on a shaft 186 and pivoted at its upper end to a link 188 connected at its forward end to the slide 158. The bent lever 184 is connected by a link 190 to a lever 192 fulcrumed at 194 and pivoted at its upper end to a link 196 which in turn is pivoted at its forward end between lugs 197 (Fig. 5) on the base plate 72. It will be understood that as the cam 180 turns in a clockwise direction, as seen in Fig. 1, the bent lever 184 swings in a counter-clockwise direction moving the inner heel form 42 with the upper thereon toward the rear part embracing molds 44 and simultaneously closing the molds on the rear part of the upper. The actuation of these parts is so timed that the molds 44 have nearly completed their closing movement while the form 42 is still about one-half an inch from the limit of its rearward movement. See Fig. 9. As the cam 180 completes its operation, the inner heel form moves rearwardly from its position in Fig. 9 to its position in Fig. 11 and the carriers 162 continue their movement toward each other compressing the springs 172 and increasing the pressure of the molds against the upper. During this final movement of the inner heel form, it exerts a wedging action on the molds causing them to move away from each other slightly against the yielding resistance of the springs 172, into their position shown in Fig. 11, wiping the upper about the form 42, and obviating any pinching or creasing of the upper which might occur if the molds were to close on the upper without such separation of their rear portions during the latter part of their closing movement.

The form 42 and the molds 44 complete their operation at an early stage in the machine cycle and during the remaining operations of the machine, the upper is firmly held between the form 42 and the molds by the cam 180 which, as seen in Fig. 1, has a long dwell extending around more than one-half the periphery of the cam.

After the form 42 and the molds 44 have completed their operation and gripped the rear part of the upper between them, the rear-part wiper member 56 is actuated to bend the lasting margin of the upper over the edge of the form 42 and wipe it inwardly over the heel seat face of the form. Referring to Figs. 13, 14, and 16, the wiper member 56 is a generally rectangular plate having a V-shaped notch 198 in its forward portion the edges of which engage the lasting margin of the upper to perform the wiping operation. The wiper is carried by a slide 200 (Figs. 13 and 14) mounted in longitudinal grooves in the plates 202. Referring to Fig. 16, the wiper is secured to the slide 200 by screws 210 two of which extend upwardly through open-ended slots 212 in the rear part of the wiper while the forward screws 210 (Fig. 13) extend downwardly through holes in the slide 200 and are threaded into tapped holes in the wiper. It will be seen that only the forward screws need be disengaged from the wiper to permit the wiper to be removed from the machine. Referring to Fig. 15,

the wiper is automatically operated by a cam 214 on the shaft 52 which cam acts against a roll 216 on a bent lever 218 pivoted on the shaft 186, the upper portion of said lever being bent forwardly and connected by a link 220 to lugs 222 on the slide 200.

Referring now to the construction and operation of the flange former 58 (Fig. 19), the illustrated flange former is a metal block or die having a peripheral contour similar to the heel seat portion of a shoe and having downwardly converging bottom faces 224 which engage the overwiped margins of the upper materials and press them downwardly into a concave recess 226 in the inner heel form 42, which, it will be understood, acts as a female die in the flange-forming operation. The flange former over-molds the overwiped margins of the upper materials to a predetermined extent such that the normal spring-back of the margin of the counter in the upper will leave the overwiped margins in the proper position for attachment to an insole, or substantially in a common plane. The flange former is removably secured by screws 228 to the bottom face of a slide 230. Referring to Figs. 13 and 14, the illustrated slide is mounted in a guideway in an upward extension 232 of the slide 200 for movement in a path at right angles to the path of movement of the slide 200, the movement of the slide 230 being directed and controlled by tongue and groove connections 233 (Fig. 14) between the slide and the extension 232. The flange former assembly moves forwardly with the wiper assembly during the wiping operation, this movement of the wiper assembly transferring the flange former from its position remote from the upper 142, illustrated in Fig. 13, to a position directly over the rear part of the upper. In its operation the flange former moves heightwise of the upper through an opening 234 (Fig. 16) provided in the wiper member 56 and into the concave recess in the form 42 (Figs. 15 and 19). For operating the flange former, a cam 236 (Fig. 15) on the cam shaft 52 is constructed and arranged to act against a roll 238 on an arm 240 fast on the shaft 186. An arm 241 fast on the remote end of said shaft, as seen in Fig. 15, has swiveled to its upper end a block 242 (Figs. 14 and 15) slidably mounted on a rod 244 pivoted to an arm 246 secured to one end of a shaft 247, said shaft being journaled in upward extensions 248 on one of the plates 202. An arm 254 secured to the forward end of the shaft 247 has swiveled at its forward end a block 256 constructed and arranged to slide in a longitudinal slot 258 provided in a lever 260 fulcrumed at 262 on the upward extension 232 of the wiper slide 200. The lever 260 is connected by links 264 to the slide 230 which carries the flange former 58. During the operation of the wiper member 56, the slot 258 in the lever 260 is parallel to the wiper slide 200 and the lever 260 moves longitudinally relatively to the block 256 without moving the flange former. In the operation of the machine, the block 242 on the arm 241 is moved forwardly or to the left, as seen in Fig. 15, acting against a spring 250 surrounding the rod 244 and confined between the block 242 and nuts 252 on the rod. During the latter part of the movement of the arm 241 after the flange former has entered the concave recess in the form 42, the arm compresses the spring 250 thus increasing the pressure of the flange former against the overwiped margins of the upper materials.

Referring now to the construction and operation of the instep-stretching and-shaping member (Figs. 3 and 4) said member comprises a form 268 removably secured to a lever 270 by a headed screw 272. The form 268, as shown in Fig. 4, has a convex bottom surface which in the operation of the member acts against the inner surface of the instep portion of the upper. The lever 270 is pivoted to a slide 274 mounted in a T-way provided in the bottom of the extension 68 of the L-shaped member 70. The instep-shaping member is yieldingly held at the limit of its upward movement by a leaf spring 276 secured to the lever 270, the front end of said spring being upturned for engagement with the bottom surface of the extension 68. For operating the instep-shaping member, a slide 278 (Fig. 15) is splined in a bore provided in a bracket 280 extending inwardly and upwardly from the front of the frame 30. The slide 278 has at its upper end a forwardly extending arm 282 which carries a roll 284 which engages the top of the lever 270 when the inner heel form 42 is at the limit of its rearward movement. For moving the slide 274 downwardly to operate the instep-shaping member a cam 286 (Fig. 22) on the cam shaft 52 is constructed and arranged to act against a roll 288 on a lever 290 which swings on a fixed fulcrum 292 and is connected by a link 294 to the lower end of the slide 278. When the machine is at rest, as seen in Fig. 1, the rear end of the lever 270 is spaced away from the roll 284 sufficiently to permit an upper to be moved upwardly between the lever and the roll preparatory to assembling the upper on the inner heel form 42.

In the operation of the machine, as herein illustrated, a closed upper, for example, the upper 142 illustrated in Fig. 7, is moved upwardly by the operative from a position beneath the inner heel form 42 into the position illustrated in Fig. 7, this position being determined by the engagement of the edge of the lasting margin of the upper with the gage members 144. The back seam of the upper, where the upper has a back seam, is centered between the inner ends of the gage members (Fig. 6). Where the upper has no back seam the lasting margin is preferably notched to indicate the point which should be centered between the inner ends of the gage members. After the rear part of the upper has been positioned on the form 42 the toe end of the upper is placed between the toe gripper jaws 92 and 100 (Fig. 7) and the jaws are closed by the operation of the hand lever 110. The lasting margin of the upper, or, if desired, the lasting margin of the lining only, at opposite sides of the ball portion is then positioned between the jaws of the side grippers whereupon the side grippers are closed simultaneously by the operation of the hand lever 80. In positioning the lasting margin in the side grippers, the operative wraps the upper about the instep-stretching and-shaping member to arrange it for the instep-shaping operation. The operative now depresses the treadle 54 to start the machine. Immediately upon depression of the treadle, the inner heel form 42 moves toward the rear-part shaping molds 44 and the molds close while the gage members 144 swing outwardly from their position illustrated in Fig. 6 to their position illustrated in Fig. 9 in order to provide clearance for the advancement of the wiper-carrying slide 200. During the advancement of the form 42, the side grippers move upwardly to stretch the upper heightwise about the instep-shaping member.

The side grippers and the toe gripper are yieldingly held against rearward movement with the inner heel form 42 by the springs 118 and 120 (Fig. 20) and these springs act during the advancement of the form 42 to tension the upper lengthwise. Thus, it will be seen that the upper is drawn tightly about the end of the form 42 as the form advances and is also drawn tightly about the instep-shaping member. Thus, when the form 42 comes to the limit of its advancement, the grippers will have positioned the upper for the various operations of the machine thereon and the upper will be securely held by the grippers until the machine has completed its operations. During the advancement of the form 42, the molds 44 are closed on the rear part of the upper by the operation of the slide 158 (Figs. 6, 9, and 11) acting through the arms 178 to swing the mold carriers from their position illustrated in Fig. 6 into their position illustrated in Fig. 11. The closing of the molds 44 on the rear part of the upper is completed just before the inner heel form 42 comes to the limit of its advancement and as the form 42 completes its advancement, it exerts a wedging action on the molds 44 against the yielding resistance of the springs 172 (Fig. 6) spreading them slightly into the position illustrated in Fig. 11 and obviating any pinching or creasing of the back-seam portion of the upper by the molds. After the rear part of the upper has been thus gripped against the form 42 by the molds 44, the wiper member 56 advances from its rest position, illustrated in Figs. 1 and 16, into its position illustrated in Fig. 18 wiping the last margin of the rear part of the upper inwardly over the heel-seat portion of the form 42. After the wiper member has completed its wiping operation, it continues to advance into its position illustrated in Fig. 18 in order to position the flange former 58 in alignment with the concave recess 226 (Fig. 19) in the form 42. The flange forming member is now moved downwardly through the opening 234 provided in the wiper member 56 and pressed hard against the overwiped margins of the upper materials, overmolding them to a predetermined extent such that their normal spring-back will position them for attachment to an insole. During the operation of the flange molding member the instep-stretching and-shaping member is operated by the cam 286 (Fig. 22) which moves the slide 278 downwardly, said slide acting on the lever 270 of the instep-shaping member. It will be understood that the lever 270 is positioned beneath the roll 284 carried by the slide 278 in the course of the advancement of the inner heel form 42. After the instep-shaping member has completed its operation, the entire machine head including the wiper assembly and the flange-former assembly are swung upwardly to separate the wiper and the flange-former from the molded margin of the rear part of the upper, thus permitting the wiper to be retracted without danger of dislocating or disfiguring the molded margin of the upper. For swinging the head upwardly, the illustrated machine is provided with two duplicate cam mechanisms arranged at opposite sides of the machine and connected respectively to the forward portions of the plates 202 which form the base of the swinging head. Referring to Fig. 1, which illustrates the cam mechanism connected to the plate 202 at the left of the machine, a cam 298 on the shaft 52 is provided with a groove 300 in which is mounted a roll 302 carried at the lower end of a rod 304 slidably mounted in a

bearing in a bracket 306 extending inwardly from the inner surface of the frame 30, the rod 304 being pivotally connected to the plate 202 at the left of the machine. After the head is swung upwardly by the operation of the duplicate cam mechanisms, the flange molding member is moved upwardly into its rest position and the wiper member 56 is retracted and, at the same time, the slide 278 (Fig. 22) moves upwardly permitting the return of the instep shaping member to its rest position by the spring 276 (Fig. 3). Thereupon, the rear part shaping molds 44 open and the inner heel form 42, together with the upper gripping assemblies, moves forwardly into its rest position. The operative then disengages the gripper members from the upper and removes the upper from the machine.

While the operation of the illustrated machine has been described with reference to the shaping of a closed upper, it will be understood that the utility of the machine is not limited to the shaping of closed uppers since it is well adapted to operate on quarters or back parts which have not been stitched to their vamps. In operating on such back parts the operative will manually tension the back part about the inner heel form as the form advances into the molds, the toe grippers and side grippers remaining idle. After the molds close on the back part and grip it against the form, they control the position of the back part and no further attention thereto by the operative is required. The operation of the molds, the wiper, and the flange former will proceed as hereinbefore described, operating on the back part in exactly the same manner as they operate on a closed upper. The molded back part thus provided requires no further shaping but is ready for attachment to a sole.

Having thus described my invention, what I claim as new and desire to secure by Letters Patent of the United States is:

1. In an upper-shaping machine, means for shaping an end portion of an upper, means for holding the upper under lengthwise tension during the shaping operation, and means for applying pressure to the instep portion of the upper in a direction generally heightwise of the upper to shape said instep portion while the upper is held by said shaping means and said tensioning means.

2. In an upper-shaping machine, means for shaping the rear part of an upper comprising an inner heel form and rear part embracing means for pressing the upper against the form, means for holding the upper under lengthwise tension during the heel shaping operation, and means for applying pressure to the instep portion of the upper in a direction generally heightwise of the upper to shape said instep portion while the upper is held by said shaping means and said tensioning means.

3. In an upper-shaping machine, means for shaping the rear part of an upper, means for holding the upper under lengthwise tension, means for holding the forepart of the upper under heightwise tension, and means for applying pressure to the instep portion of the upper in the general direction of the height of the upper to shape said instep portion while the upper is held by said shaping means and said tensioning means.

4. In an upper-shaping machine, an inner heel form, a pair of rear part shaping molds constructed and arranged to act against the form, carriers for the molds, said molds being movable away from each other after the carriers have

closed the molds on an upper on the heel form, means for advancing the form and the upper thereon into the molds, wedging the molds apart from each other, means for applying lengthwise tension to the upper during the advancement of the form, and means for applying heightwise tension to the forepart of the upper while the rear part of the upper is held between the form and the molds.

5. In an upper-shaping machine, an inner heel form, means for shaping the rear part of an upper against the form, means for gripping the toe end of an upper on the form, means for gripping opposite side portions of the upper, means for operating said toe gripping means and said side gripping means to tension the upper longitudinally thereof against said form, means for varying the tension of the toe gripping means on the upper, and means for independently varying the tension of the side gripping means on the upper.

6. In an upper-shaping machine, an inner heel form, means for shaping the rear part of an upper against the form, means for moving the form lengthwise of the upper toward the shaping means, means for gripping the toe end of the upper, means for gripping opposite side portions of the upper, and means operated by said movement of the form to cause said gripping means to tension the upper longitudinally against the form.

7. In an upper-shaping machine, an inner heel form, means for shaping the rear part of an upper against the form, a carrier for the form movable toward and from the shaping means, means for gripping the toe end of the upper on the form, means for gripping opposite side portions of the upper, a fixture adjacent to the toe end of the upper, and yielding connections between the gripping means and the fixture.

8. In an upper-shaping machine, an inner shoe form, means for shaping the rear part of an upper about the form, a carrier for the form constructed and arranged for movement toward and from the shaping means, grippers mounted on the carrier and arranged to engage opposite side portions of an upper on the form, said grippers being movable relatively to the carrier generally lengthwise of an upper on the form, means for varying the tension of the toe gripping means on the upper, and means for independently varying the tension of the side gripping means on the upper.

9. In an upper-shaping machine, an inner shoe form, means for shaping the rear part of an upper about the form, a carrier for the form constructed and arranged for movement toward and from the shaping means, grippers mounted on the carrier and arranged to engage opposite side portions of an upper on the form, said grippers being movable relatively to the carrier generally lengthwise of an upper on the form, a toe gripper, a fixture on which the toe gripper is mounted for movement lengthwise of the upper, means for varying the tension of the toe gripping means on the upper, and means for independently varying the tension of the side gripping means on the upper.

10. In an upper-shaping machine, an inner heel form, means for shaping the rear part of an upper about the form, a carrier for the form movable longitudinally of the upper toward the shaping means, grippers mounted on the carrier and arranged to engage opposite side portions of the upper, said grippers being movable relatively to the carrier generally lengthwise of the upper, and means operating during said movement of

the carrier to cause said grippers to tension the upper lengthwise against the form.

11. In an upper-shaping machine, an inner heel form, means for shaping the rear part of an upper upon the form, a carrier for the form movable lengthwise of an upper thereon toward and from the shaping means, a slide mounted on the carrier for movement generally lengthwise of the upper on the form in a path inclining downwardly and rearwardly relatively to the upper, and grippers carried by the slide and constructed and arranged to engage opposite sides of the lasting margin of the upper.

12. In an upper-shaping machine, an inner heel form, means for shaping the rear part of an upper upon the form, a carrier for the form movable lengthwise of the upper toward and from the shaping means, a slide mounted on the carrier for movement generally lengthwise of the upper in a path inclining downwardly and heelwardly relatively to the upper, grippers carried by the slide and constructed and arranged to engage opposite sides of the lasting margin of the upper, and means for urging said slide forwardly of the upper.

13. In an upper-shaping machine, an inner heel form, means for shaping the rear part of an upper about the form, a carrier for the form movable lengthwise of the upper toward the shaping means, a slide mounted on the carrier for movement generally lengthwise of the upper in a path inclining downwardly and heelwardly relatively to the upper, grippers carried by the slide and constructed and arranged to engage opposite sides of the lasting margin of the upper, and means operating automatically during said movement of the carrier to cause the grippers to tension the upper lengthwise against the form.

14. In an upper-shaping machine, an inner form, a pair of end-embracing molds constructed and arranged to operate on an end portion of an upper on the form, means for closing the molds on said end portion, and means for effecting relative movement of the molds and the form toward each other, the latter part of such movement occurring after the molds have completely closed and causing a separation of the adjacent end portions of the molds by wedging action of the form.

15. In an upper-shaping machine, an inner form, a pair of end-embracing molds constructed and arranged to operate on an end portion of an upper on the form, means for closing the molds, and means for moving the form into the molds, the latter part of such movement of the form occurring after the molds have completely closed and causing a separation of the adjacent end portions of the molds by wedging action of the form.

16. In an upper-shaping machine, an inner form, a pair of end-shaping molds, carriers for the molds, said molds being movable away from each other after the mold carriers have closed the molds on an upper on the form, a carrier for said form constructed and arranged for movement lengthwise of the upper, and means for operating the carrier to advance the form and the upper thereon into the molds wedging the molds apart from each other.

17. In an upper-shaping machine, an inner form, a pair of end-shaping molds, carriers for the molds constructed and arranged to swing on fixed axes, said molds being movable widthwise of an upper on the form relatively to their carriers, a carrier for said form constructed and arranged for movement lengthwise of the upper,

and means for operating the carrier to advance the form and the upper into the molds wedging the molds apart from each other.

18. In an upper-shaping machine, an inner form, a pair of end-shaping molds, carriers for the molds constructed and arranged to swing on fixed axes, said molds being movable widthwise of an upper on the form relatively to their carriers, said form being constructed and arranged for movement lengthwise of the upper, and an actuator for simultaneously closing the molds and advancing the carrier and an upper thereon into the molds, the closing of the molds being completed before the form comes to the limit of its advancement so that the form during the latter part of its advancement wedges the molds apart from each other.

19. In an upper-shaping machine, an inner form, a pair of molds constructed and arranged to operate on an end portion of an upper on the form, carriers for the molds constructed and arranged to swing on fixed axes located rearwardly of said form and spaced apart from each other widthwise of the form, said molds being movable widthwise of the form relatively to their carriers, a carrier for said form constructed and arranged for movement lengthwise of the form, and means for operating the carrier to advance the form into the molds wedging the molds apart from each other.

20. In an upper-shaping machine, an inner form, a pair of molds constructed and arranged to operate on an end portion of an upper on the form, carriers for the molds constructed and arranged for movement generally widthwise of the form, said molds being movable widthwise of the form relatively to their carriers, yielding resistance means interposed between the carriers and the molds, and means for advancing the form into the molds wedging the molds apart from each other against the resistance of said yielding resistance means.

21. In an upper-shaping machine, an inner form, a pair of molds constructed and arranged to operate on an end portion of an upper on the form, carriers for the molds constructed and arranged to swing on fixed axes located rearwardly of said form and spaced apart from each other widthwise of the form, said molds being movable widthwise of the form relatively to their carriers, yielding resistance means interposed between the carriers and the molds, a carrier for said form constructed and arranged for movement lengthwise of the form, and means for operating the carrier to advance the form into the molds wedging the molds apart from each other against the resistance of said yielding resistance means.

22. In an upper-shaping machine, an inner form, a pair of end-shaping molds having rigid work-engaging faces complementary in contour to the periphery of the form, the adjacent end portions of said work-engaging faces having a total width less than the width of said form, carriers for the molds, said molds being movable away from each other after the mold carriers have closed the molds, and means for advancing the form into the molds wedging the molds apart from each other.

23. In an upper-shaping machine, means for holding the forepart of an upper by its lasting margin against bodily heightwise movement, and means constructed and arranged to operate locally against the inner surface of the instep portion only of the upper to stretch said instep portion relatively to the rest of the upper.

24. In an upper-shaping machine, means for gripping the forepart of an upper by its lasting margin at both sides of the upper, an instep-shaping member constructed and arranged to engage the inner surface of the instep portion only of the upper, and means for effecting relative movement of said gripping means and said instep-shaping member generally heightwise of the upper to stretch said instep portion relatively to the rest of the upper.

25. In an upper-shaping machine, means for holding the forepart of an upper by its lasting margin against bodily heightwise movement, an instep-shaping member constructed and arranged to operate against the inner surface of the instep only of the upper, and means for moving the instep-shaping member generally heightwise of the upper to stretch the instep portion of the upper relatively to the rest of the upper.

26. In an upper-shaping machine, an upper-receiving form, means for holding the forepart of an upper on the form by its lasting margin, an instep-shaping member carried by the form and constructed and arranged to operate against the inner surface of the instep portion of the upper, and an actuator for said instep-shaping member.

27. In an upper-shaping machine, an upper-receiving form, means for holding the forepart of an upper on the form by its lasting margin, an instep-shaping member carried by the form and constructed and arranged to operate against the inner surface of the instep portion of the upper, and an actuator for said instep-shaping member, said form being movable in a direction to separate the instep-shaping member from its actuator.

28. In an upper-shaping machine, an upper-receiving form, means for holding the forepart of an upper on the form by its lasting margin, an instep-shaping member carried by the form and constructed and arranged to operate against the inner surface of the instep portion of the upper, an actuator for said instep-shaping member, and means for automatically moving said form in a direction to separate the instep-shaping member from its actuator.

29. In an upper-shaping machine, means for holding the forepart of an upper by its lasting margin, means for holding the rear part of the upper comprising an inner heel form and rear part embracing means, and an instep-shaping member constructed and arranged to operate against the inner surface of the instep portion of the upper while the forepart and the rear part are held by said holding means.

30. In an upper-shaping machine, means for holding the forepart of an upper by its lasting margin, means for holding the rear part of the upper comprising an inner heel form and rear part embracing means, and an instep-shaping member mounted on said inner heel form and constructed and arranged to operate against the inner surface of the instep portion of the upper while the forepart and the rear part are held by said holding means.

31. In an upper-shaping machine, an inner shoe form, means for tensioning an upper lengthwise against said form, a wiper for wiping the lasting margin of an end portion of the upper on the form inwardly over the sole portion of the form, and a flange former which has operative movement heightwise of the form and no operative movement lengthwise of the form.

32. In an upper-shaping machine, an inner shoe form, a wiper for wiping the lasting margin

of an end portion of an upper on the form inwardly over the heel seat face of the form, a flange former constructed and arranged to operate on the overwiped margin of said end portion, means for operating the flange former after the wiper has come to rest, and means for stretching the instep portion of the upper while the upper is held against the form.

33. In an upper-shaping machine, an inner shoe form, means acting on the toe portion of an upper to hold it against said form, a wiper for wiping the lasting margin of an end portion of the upper on the form inwardly over the heel seat face of the form, means for moving the wiper in the direction of the length of the form, a flange former constructed and arranged to operate on the overwiped margin of said end portion, and means for operating the flange former after the wiper has completed its operation.

34. In an upper-shaping machine, an inner shoe form, means acting on opposite sides of the forepart of an upper to hold it against said form, a wiper for wiping the lasting margin of an end portion of the upper on the form inwardly over the sole portion of the form, a flange former which has operative movement heightwise of the form and no operative movement lengthwise of the form, and means for holding said end portion against the form.

35. In an upper-shaping machine, an inner heel form, grippers acting at the toe and the forepart of an upper for holding it against said form, a wiper for wiping the lasting margin of the rear part of the upper on the form inwardly over the heel seat face of the form, a flange former constructed and arranged to operate on the overwiped margin of the upper, means for operating the flange former after the wiper has come to rest, a rear part embracing member for holding the rear part of the upper against the inner heel form, and means for holding the rear part embracing member in rear part embracing position during the operation and retraction of the wiper and the flange former.

36. In an upper-shaping machine, an inner form, a wiper for wiping the lasting margin of the rear part of an upper on the form inwardly over the sole face of the form, a carrier on which the wiper is rigidly mounted, means for moving the carrier toward the form in the direction of the length of the upper to operate the wiper, and means for automatically lifting the wiper away from the upper in predetermined time relation to the lengthwise movement of the wiper.

37. In an upper-shaping machine, an inner form, a toe gripper, grippers acting at opposite sides of the forepart of an upper, means for causing said toe gripper and side grippers to tension the upper lengthwise against said form, a wiper for wiping the lasting margin of an end portion of the upper on the form inwardly over the sole face of the form, a carrier on which the wiper is mounted for movement lengthwise of the upper, a flange former, and means operating after the wiper has come to the limit of its advancement to move the flange former heightwise of the upper to press the overwiped margin of the upper against the form.

38. In an upper-shaping machine, an inner form, a wiper for wiping the lasting margin of an end portion of an upper on the form inwardly over the sole face of the form, a carrier on which the wiper is mounted for movement lengthwise of the upper, a flange former, means operating after the wiper has come to the limit of its ad-

vancement to move the flange former heightwise of the upper to press the overwiped margin of the upper against the form, and means for moving the wiper and the flange former heightwise of the upper away from the heel form before the wiper is retracted.

39. In an upper-shaping machine, a wiper for wiping inwardly the lasting margin of an end portion of an upper, a carrier on which the wiper is mounted for movement lengthwise of the upper, a head provided on said carrier and disposed generally heightwise of the upper, a flange former slidably mounted in said head and constructed and arranged to operate on the overwiped margin of the upper, means for operating said flange former including a lever having a guideway which, when the flange former is retracted, is parallel to the path of movement of said carrier, and a pivot member slidably mounted in said guideway.

40. In an upper-shaping machine, a wiper for inwardly wiping the lasting margin of an upper, a carrier on which the wiper is rigidly mounted, a head in which the carrier is slidably mounted, a standard on which the head is mounted for movement generally heightwise of the upper, and means for automatically moving the head in predetermined time relation to the operation of the wiper to disengage the wiper from the overwiped margin of the upper.

41. In an upper-shaping machine, an inner heel form, a pair of rear part shaping molds constructed and arranged to operate against an upper on the form, a wiper for wiping the lasting margin of the upper inwardly over the heel seat face of the form while the rear part is held between the form and the molds, a carrier on which the wiper is rigidly mounted, means for moving the wiper toward and over the form in the direction of the length of the upper, and means for lifting the wiper away from the upper before the wiper is retracted.

42. In an upper-shaping machine, an inner heel form having a recessed heel seat face, means for tensioning an upper lengthwise against said form, a die for shaping the margin of the upper against said heel seat face, means for effecting relative movement of the die and the form heightwise only of the upper to shape the margin of the upper against the form, and means for wiping the lasting margin of the upper inwardly over the heel seat face of the form to locate said margin in position to be operated upon by said die.

43. In an upper-shaping machine, an inner heel form, a pair of rear part shaping molds constructed and arranged to operate on an upper on the form, a wiper for wiping the lasting margin of the upper inwardly over the form while the rear part of the upper is held between the form and the molds, a carrier on which the wiper is mounted for movement lengthwise of the upper, a flange former mounted in the carrier, means operating after the wiper has come to the limit of its advancement to move the flange former heightwise of the upper to press the overwiped margin of the upper against the heel form, and means for moving the carrier in a direction to disengage the wiper and the flange former from the upper before said members are retracted.

44. In an upper-shaping machine, means for holding the forepart of an upper by its lasting margin, means for holding the rear part of the upper comprising an inner heel form and upper

embracing means constructed and arranged to grip the upper against the form, a wiper for wiping the lasting margin of the rear part of the upper inwardly against the heel seat face of said form, and means for stretching the instep portion of the upper, said wiper and said instep-stretching means operating while the upper is held by said holding means.

45. In an upper-shaping machine, means for holding the forepart of an upper by its lasting margin, means for holding the rear part of the upper comprising an inner heel form and upper embracing means constructed and arranged to grip the upper against the form, a wiper for wiping the lasting margin of the rear part of the upper inwardly against the heel seat face of said form, an instep-shaping member carried by the form and constructed and arranged to operate against the inner surface of the instep portion of the upper, and an actuator for said instep-shaping member.

46. In an upper-shaping machine, an inner

heel form, rear part embracing means for shaping an upper against the form, a carrier therefor, a gage member for determining the position of the upper heightwise thereof on the form, a wiper for wiping the lasting margin of the rear part of the upper over the form, and connections from said carrier to said gage member for retracting the gage member as the wiper is advanced.

47. In an upper-shaping machine, an inner heel form, a pair of gage members constructed and arranged to engage the edge of the lasting margin of an upper on the form and position the upper heightwise thereof, rear part embracing means for shaping the upper against the form, a carrier therefor, a wiper for wiping the lasting margin of the rear part of the upper over the form, and connections from the carrier to said gage members for moving said members away from each other into positions remote from the path of movement of the wiper.

KARL ENGEL.
